[57] CLAIM

The ornamental design for a scanning camera, as shown and described.

DESCRIPTION

FIG. 1 is a top and right front perspective view of a scanning camera showing my new design in the raised and lamp extended position;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof;

FIG. 7 is a bottom plan view thereof;

FIG. 8 is a cross-sectional view thereof as taken from line 8—8 of FIG. 1;

FIG. 9 is a top and right front perspective view of the design of FIGS. 7—8 in its lowered position with lamps folded;

FIG. 10 is a front elevational view thereof;

FIG. 11 is a rear elevational view thereof;

FIG. 12 is a top plan view thereof;

FIG. 13 is a right side elevational view thereof;

FIG. 14 is a left side elevational view thereof;

FIG. 15 is a bottom plan view thereof;

FIG. 16 is a cross-sectional view thereof as taken from line 16—16 of FIG. 9.
